UNITED STATES PATENT OFFICE.

KATHERINE LEROY WATKINS, MARY LOUISE GROFF, AND GEORGE WILSON HEARD,
OF CHICAGO, ILLINOIS.

MOP AND WRINGER.

Application filed March 16, 1923. Serial No. 625,492.

To all whom it may concern:

Be it known that we, KATHERINE LEROY WATKINS, MARY LOUISE GROFF, and GEORGE WILSON HEARD, citizens of the United States, 5 residing at Chicago, in the county of Cook and State of Illinois, have invented a new and useful Mop and Wringer, of which the following is a specification.

The present invention has to do with mops 10 and mop wringers, and relates particularly to the combination of the mop and wringer upon the mop handle.

The primary object of the invention is to provide a combination of mop and wringer 15 parts whereby the strands of the mop will be advantageously grouped at the end of the handle when the device is in use, and will permit of the strands being forcibly compressed about such mop-handle for purposes 20 of compressing liquid therefrom.

A secondary object of the invention is to provide improved means for gripping the mop strands during a rotative wringing motion, and a unique strand holding device 25 movable along the mop-handle.

These, and such other objects as may hereinafter appear, are attained by the novel construction, combination, and arrangement of the several parts of our device, which is illustrated in the accompanying drawing attached to and made a part of this specification, and in which:—

Fig. 1 is an elevation of a mop with its strands separated to show details of construction;

Fig. 2 is an elevation of the device while the mop strands are being wrung out;

Fig. 3 is an elevation showing the mop in operable position;

Fig. 4 is a transverse section on the line 4—4 of Fig. 1;

Fig. 5 is a similar section along the line 5—5 of Fig. 1; and

Fig. 6 is a fragmentary elevation showing 45 the end of the mop-handle with the mop removed.

Like reference characters are used to designate similar parts in the drawing and in the description which follows.

The device comprises a mop-handle 10 of the usual cylindrical form terminating in a flat end, and of any desired length.

Strands 11 of the mop are arranged circumferentially about mop-handle 10 in sev-

eral layers, and a circumferential wrapping 55 or binder 12 for one thereof is provided adjacent the end of the handle 10.

A collar 13 is loosely mounted upon mop-handle 10. Such collar comprises an elongated grip portion 14 for facilitating movement of such collar either longitudinally or rotatively upon handle 10, a wide circumferential groove 15 shown in dotted lines in Fig. 4, and a toothed inner end 16. The toothed portion 16 comprises a plurality of 60 regularly spaced radial projections adapted to engage a limited number of strands 11 during rotative movement of collar 13, such strands being secured at their other ends in the grooved or ring seat 15 by a circumferential binder or wrapper 17, similar to that employed at the end of the mop and indicated by the numeral 12.

Adjacent the extremity of the mop is a 65 lock member 18 comprising a flat piece of metal, preferably of spring or bendable material, secured by fastenings 19 to the periphery of the mop-handle 10. Such locking member is best illustrated in Figs. 1 and 5, and it is shown in said figures that the metal 70 thereof is bowed outwardly before attachment to the handle 10.

In order to use the device as a mop, the collar 13 is forced downwardly upon the 75 mop-handle 10 and over the locking member 18 thus causing the metal thereof to buckle and bend to frictionally engage said collar. The strands 11 are made to spread out and form in a bunch. The strands in this position are best shown in Fig. 3.

When it is desired to wring the mop, collar 13 is drawn back on the handle 10 as far as permitted by the fastenings for strands 11 and then turned by the hand applying rotative force to portion 14 thereof. Rotating 80 collar 13 either to the right or to the left will express the water from strands 11 by compression upon handle 10. The teeth 18 separate strands 11 into a series of small 85 groups and prevent their slipping, or the slipping of collar 13, during the rotary compressing movement described. Said teeth also relieve the strain otherwise to be borne by the circumferential wrapping 17.

The locking portion 18, while securely 90 holding the collar 19 against accidental displacement when the mop is used in the position shown in Fig. 3, does not provide suf-

ficient resistance against the withdrawal of the collar 13 from engagement therewith to make the change in position difficult.

- Reference should now be had to Fig. 6.
- 5 In the preferred construction, the mop-handle 10 is formed with a spurred or toothed end 20 and has a circumferential groove 21 cut contiguous thereto. Strands 11 are spread over and about such toothed end 20 and then drawn upwardly on handle 10 as previously indicated. The circumferential band 12 is wrapped securely about the strands 11 so disposed and is seated thereupon within the groove 21. In this manner 15 rotation of strands 11 on the mop-handle 10 is securely resisted and slippage during the wringing motion wholly avoided.

We claim:

A mop comprising a handle, and strands secured at one end to said handle, a collar 20 slideable and rotatable upon said handle and to which the other ends of said strands are secured, said collar including a plurality of radially disposed fingers adapted to engage limited numbers of said strands during rotative movement of said collar, and a lock member adjacent the end of said handle, said lock member comprising a metal strip bowed at its middle and secured at its ends, said collar frictionally engaging said lock member when the mop is in operable position. 25
